(57) **CLAIM**

The ornamental design for the medical injector, as shown and described.

DESCRIPTION

The file of this patent contains at least one photograph executed in color. Copies of this patent with color photographs will be provided by the Office upon request and payment of the necessary fee.

FIG. 1 is a right side view of the medical injector of our new design:

FIG. 2 is a front view thereof;

FIG. 3 is a left side view thereof;

FIG. 4 is a rear view thereof;

FIG. 5 is a perspective thereof;

FIG. 6 is a top view thereof;

FIG. 7 is a bottom view; and,

FIG. 8 is a bottom perspective view.

The colors of the design are as follows:

Body: sky blue;

Dose dial grip: light blue-gray; and

Dose button: royal blue.

1 Claim, 4 Drawing Sheets
